UNITED STATES PATENT OFFICE.

FRANK FRASHER, OF IRENTON, OHIO.

STOVE-VENTILATOR.

SPECIFICATION forming part of Letters Patent No. 586,174, dated July 13, 1897.

Application filed March 30, 1897. Serial No. 629,921. (No model.)

To all whom it may concern:

Be it known that I, FRANK FRASHER, a citizen of the United States, residing at Ironton, in the county of Lawrence and State of Ohio, have invented certain new and useful Improvements in Stove-Ventilators; and I do hereby declare the following to be a full, clear, and exact description of the invention, such as will enable others skilled in the art to which it appertains to make and use the same.

My invention has relation to adjustable ventilators, and more particularly to that class employed in ovens or other closed chambers, air-ducts, and the like; and the object is to provide a simple, convenient, and effective device for this purpose.

To these ends the novelty consists in the construction, combination, and arrangement of the same, as will be hereinafter more particularly pointed out in the claims.

In the accompanying drawings the same reference-characters indicate the same parts of the invention.

Figure 1 is an external perspective view of my improved adjustable ventilator. Fig. 2 is a perspective view taken from the inside of the ventilator. Fig. 3 is a horizontal section, and Fig. 4 a vertical section, showing the ventilator open.

1 represents the frame-plate, provided with a circular orifice 2, having converging walls 3 3.

4 represents a parallel bracket extending across the inside of orifice 2 and having its angular arms 5 5 secured to the contiguous face of said plate by screws 6 6.

The central portion of the bracket 4 is formed with a transverse circular orifice 7, arranged concentric with the orifice 2 in the plate, and 8 8 represent two oppositely disposed and alined radial recesses communicating with the central orifice 7. 9 9 represent two parallel lugs formed integral with the outer face of the bracket and on opposite sides of the orifice 7, and their outer faces are formed with reversely-arranged inclined planes 10 10.

The inner face of the bracket is provided with an integral web 11, which forms a continuation of the lower half of the orifice 7 and radial recesses 8 8.

12 represents a flat disk provided on its outer face with an integral flat handle 13, and its periphery is formed with converging edges 14 14, adapted to snugly engage the corresponding converging walls 3 3 of the orifice 2 in the frame-plate 1, and 15 represents an annular radial projecting flange which overlaps the outside edge of the orifice 2 and snugly fits the contiguous face of the plate 1.

The inner face of the disk is formed with a central shank 16, the outer end of which terminates in a transverse flat plate 17, formed with a projecting lip 18, and oppositely-disposed radial shoulders 19 19, having reversely-beveled edges 20 20, which are arranged to engage the correspondingly-inclined planes 10 10 on the bracket 4 to draw the disk 12 into intimate contact with the walls of the orifice 2 and form an air-tight joint.

When desirable to admit air through the orifice 2, the disk is turned to the left by means of its handle to release the shoulder 19 from engagement with the inclined planes 10 and bring it into alinement with the radial recesses 8 8 in the bracket 4, so as to permit the disk to be withdrawn from the orifice 2 and permit the passage of air, the amount of air so admitted corresponding to the distance at which the disk is removed, and consequently the same can be perfectly regulated.

When the disk is withdrawn, the plate 17 remains in the recesses 8 8 and rests upon the web 11, which supports the disk in its adjusted position, and when it is necessary to entirely detach the disk from the plate 1 it is first withdrawn to full limit or until the lip 18 comes in contact with the bracket 4, and the handle 13 is then raised a sufficient distance to permit the lip to pass through the recesses 8 8 in the bracket, thus releasing the disk entirely from the plate.

While my ventilator is primarily intended and particularly adapted for stoves and the like, its use is by no means confined to the same, as it will be found very convenient in the saloons and state-rooms aboard ship, storage and preserving tanks and chambers, and, in fact, all kinds of closed receptacles requiring ventilating.

Although I have specifically described the construction and relative arrangement of the several elements of my invention, I do not desire to be confined to the same, as such changes or modifications may be made as clearly fall within the scope of my invention without departing from the spirit thereof.

Having thus fully described my invention, what I claim as new, and desire to secure by Letters Patent, is—

- 10 1. An adjustable ventilator of the class described comprising a plate provided with a circular orifice, a perforated bracket secured to said plate and extending across said orifice, and provided with reversely-arranged integral inclined planes 10 10, in combination with a disk adapted to close said orifice and formed with an integral shank and plate 17 formed with oppositely-disposed radial shoulders 19 19 having reversely-beveled edges 20 20, adapted to pass through said perforation and engage said inclined planes on the bracket to removably secure said disk in the orifice

in said plate, substantially as and for the purpose set forth.

2. An adjustable ventilator, comprising the plate 1, having the circular orifice 2 formed with converging walls, the bracket 4 secured to said plate and extending across said orifice 2, and provided with the central 3c circular orifice 7, having radial recesses 8 8, and parallel lugs 9 9, provided with reversely-inclined faces 10 10 in combination with the detachable disk 12 formed with the converging edges 14 14 and annular flange 15, and the integral shank 16 and rectangular plate 17 provided with the projecting lip 18, and reversely-beveled edges 20 20 substantially as and for the purpose set forth.

In testimony whereof I affix my signature 4c in presence of two witnesses.

FRANK FRASHER.
